UNITED STATES PATENT OFFICE.

JACOB HEBEL, OF STEWARTSON, ILLINOIS.

HARNESS.

SPECIFICATION forming part of Letters Patent No. 225,826, dated March 23, 1880.

Application filed January 31, 1880.

To all whom it may concern:

Be it known that I, JACOB HEBEL, of Stewartson, county of Shelby, and State of Illinois, have invented certain Improvements in Harness; and I hereby declare the following to be a full, clear, and exact description thereof, reference being had to the accompanying drawings, making part of this specification, in which—

10 Figure 1 is a view of the end of a breech-strap with my improvement applied. Fig. 2 is a view of my improved breech-strap fastening before being applied.

15 My invention relates to the breech-bands of harness; and it consists of a metallic frame provided with proper openings for the insertion of the straps and secured to the ends of the breech-strap, as hereinafter more specifically described and claimed.

20 In order that those skilled in the art may make and use my invention, I will proceed to describe the manner in which I have carried it out.

25 In Fig. 2 of the drawings is shown a light metal casting consisting of a straight bar, A, having at one end an eye, B. The bow-shaped bar C has one end connected at the eye B and the other connected to the free end of the bar A.

30 From the apex of bar C rises a hip-strap-holding device, D, made of the side pieces, a, and the connecting cross-pieces b b, arranged alternately in different planes, one of

the cross-pieces nearest the end being provided with a projecting pin, d, for the purpose 35 of holding the hip-strap.

The casting is secured into the end of the breeching, as seen in Fig. 1, leaving the eye B at its extreme end, the bar A being entirely inclosed within the leather. By this metal 40 plate I provide means for attaching the hip-straps, which support the breeching from the back-strap, and also the straps which secure the ends of the breeching to the shafts, the latter straps passing through eyes B. The metallic plate may be struck up with a die or otherwise made without departing from the 45 spirit of my invention.

I am aware that plates similar in shape to mine have been used; but they lacked the 50 strengthening-bar A and the points were supported entirely by the leather connection. Such, however, I do not claim as my invention.

Having thus described my invention, what 55 I claim as new, and desire to secure by Letters Patent, is—

The metal frame or casting consisting of bar A, with its eye B, the curved bar C, and a strap-holding device, D, in combination with 60 a breech-strap, substantially as and for the purpose set forth.

JACOB HEBEL.

Attest:

JOHN P. SMITH,
WM. CUTHBERT.
